M. W. OTTO.

NOTICE INDICATOR AND MESSAGE RECEIVER.

APPLICATION FILED AUG. 21, 1918.

1,377,918.

Patented May 10, 1921.

Attorney.

UNITED STATES PATENT OFFICE.

MICHAEL W. OTTO, OF SUPPLY, OKLAHOMA.

NOTICE-INDICATOR AND MESSAGE-RECEIVER.

1,377,918.

Specification of Letters Patent.

Patented May 10, 1921.

Application filed August 21, 1918. Serial No. 250,898.

To all whom it may concern:

Be it known that I, MICHAEL W. OTTO, a citizen of the United States, and resident of Supply, in the county of Woodward and

5 State of Oklahoma, have invented certain new and useful Improvements in Notice-Indicators and Message-Receiver, of which the following is a specification.

This invention relates to indicators, and 10 more particularly to a device to indicate the time of return when a person has left his office or place of business, and also to announce cause of absence, or where to be found, or any other suitable data, as well as 15 providing a receptacle having a dial indicating the time and provided with a slot adapted for receiving messages and to retain the same safely until the return of said person to his place of business or his office.

20 A further object of the invention is to provide a novel and simple device of the above character, including a cabinet with a novel arrangement of parts therein for accomplishing the functions stated.

25 With the above and other objects in view, as will appear as the description proceeds, the invention comprises the various novel features of construction and arrangement of parts which will be more fully described 30 herein and set forth with particularity in the claims appended hereto.

Reference is had to the accompanying drawings forming a part of this application, in which like reference characters indicate 35 the corresponding parts throughout the several views, in which—

Figure 1 is a front elevation of my improved indicator,

Fig. 2 is a side view thereof, and

40 Fig. 3 is a vertical sectional view.

Referring to the drawings in detail, my improved universal notice indicator and message receiver is shown as comprising a casing 10 preferably of substantially rectangular form in outline, having a bottom wall 11, a rear wall 12, side walls 13, and a hinged door frame 14 at the front thereof, provided with a transparent or glass panel 15. The door is hinged as at 16 and is provided with a groove 17 adapted to receive the panel 15 from the top of the door frame, whereby to permit renewal of the same with convenience.

Arranged in the casing or safe is a dial 55 plate 18, corresponding to a clock dial and supported upon horizontal posts 19, con-

nected to the back wall 12 and extending in proximity to the front of the casing adjacent to the door panel. A minute hand 20 and an hour hand 21, are supported upon independent posts 22 and 23 projecting rearwardly of the dial and headed as shown at 24, there being an interposed expansible coil spring 25 designed to hold the hands under tension, whereby they will be held in adjusted positions to indicate the time of departure or return, or other data desired to be displayed. An apertured lug or hasp 26 is carried by one of the side walls 13 to project through a slot in the frame 14, whereby the door may 60 be secured in closed position by a padlock 27, whereby to facilitate secure closing of the casing against meddlers and others desiring to open the same without privilege. A slot 28 is also arranged at one side to receive 70 messages, a suitable cover 29 being arranged over the same to prevent the entrance of rain water.

The back of the casing is provided with an apertured lug 30 projecting above the 80 same for suspension purposes, and said back portion may be provided with suitable apertures 31 for suspending the device from a wall, if this is desired. The casing may be provided with a gable roof or top portion 32 85 projecting over the front and sides so as to prevent the entrance of rain water into the casing. This construction is shown in Fig. 1, while in Fig. 2 the top is shown sloping forwardly as indicated at 33, for similar 90 purposes, inasmuch as said top overhangs, as shown at 34.

Arranged in the bottom of the casing is a stacked card compartment provided with a stack of cards indicated at 35, having written or printed thereon the desired data to be used to indicate the return of the person or otherwise, it being understood that these cards can be written or printed on both sides to indicate the desired data. They are retained within the casing, so as to be used when desired. These cards are also prevented from being displaced forwardly when the door is opened through the medium of a pair of spring clamps 36, which 100 latter are arranged and provided with uprights 37 extending considerably above the lower front gripping jaws or springs so as to retain the cards in position and also serve to hold a card in position to be exhibited 110 through the transparent panel of the hinged door.

It will be understood that the device may be used in offices, railroad stations, church vestibules, kitchens, etc., wherever it is desired to indicate the data in question, and it 5 may be made of any material, either metal or wood, to suit the fittings or taste of the user. It is also to be understood that the hands may be set by turning the same, through the medium of the pivots thereof, 10 or by actuating the hands directly, and the spring 25 will hold the hands in adjusted position, even though the device may be vibrated. When it is desired to exhibit the required card, the same is taken from the 15 pile or stack 35 and placed in the spring clamp in front of the same when it will be visible through the transparent panel in connection with the dial, the dial bearing printed matter if desired. It will be understood that messages may be deposited within 20 the casing and retained safely for the owner until his return, thus combining in a single device, convenience for giving and receiving messages where the same will always be 25 acceptable.

From the foregoing description taken in connection with the accompanying draw-

ings, it is thought that a clear and comprehensive understanding of the construction, operation, and advantages of my invention 30 may be had, and while I have shown and described the device as embodying a specific structure, I desire that it be understood that such changes may be made in said structure as do not depart from the spirit and scope 35 of the invention as claimed.

Having thus described my invention, what I claim as new, and desire to secure by Letters Patent, is:

A device of the class described comprising a housing, a closure therefor having a transparent panel therein, a stacked card compartment in said housing opposite said closure, upright card supports in the housing adjacent said closure and between it and 40 said stacked card compartment, said supports being positioned to perform the double function of a card support to hold the card for reading through said panel and to retain the stacked cards against displacement. 45

In testimony whereof, I attach my signature hereto.

MICHAEL W. OTTO.
